(57) **CLAIM**

The ornamental design for reel assembly, as shown and described.

DESCRIPTION

FIG. 1 is a perspective view of the reel assembly;

FIG. 2 is a side view of the reel assembly;

FIG. 3 is another side view of the reel assembly;

FIG. 4 is a front view of the reel assembly;

FIG. 5 is a back view of the reel assembly;

FIG. 6 is a top view of the reel assembly; and,

FIG. 7 is a bottom view of the reel assembly.
